UNITED STATES PATENT OFFICE.

DE WANE B. SMITH, OF DEERFIELD, ASSIGNOR TO CHARLES H. POOLE,
OF ONEIDA, NEW YORK, AND THE NATIONAL HARROW COMPANY, OF
NEW YORK.

HARROW.

SPECIFICATION forming part of Letters Patent No. 449,649, dated March 31, 1891.

Application filed January 30, 1890. Serial No. 338,668. (No model.)

To all whom it may concern:

Be it known that I, DE WANE B. SMITH, of Deerfield, in the county of Oneida and State of New York, have invented new and useful 5 Improvements in Harrows, of which the following, taken in connection with the accompanying drawings, is a full, clear, and exact description.

My invention relates to an improved harrow, and has for its object the production of a simple and effective device, which at a minimum cost of manufacture is particularly strong, efficient, durable, and pleasing in appearance; and to this end my invention 10 consists, essentially, in frame-bars intersecting one another, spring harrow-teeth secured to the harrow-bars, a downward bend or loop formed in the tooth beneath the plane of the harrow-bars, forming a runner therefor, with the metal of the tooth bent forwardly and upwardly from said loop or downward bend and in front of the intersecting point of the harrow-bars, whereby the clogging of the harrow-frame is absolutely prevented, and 15 20 25

for, with the metal of the tooth bent forwardly and upwardly from said loop or downward bend and in front of the intersecting point of the harrow-bars, whereby the clogging of the harrow-frame is absolutely prevented, and 20 a leveling-bar beneath and supported by the forward harrow-bar for leveling the material to be harrowed and preventing diving or irregular movement of the harrow.

The invention also consists in the detail 30 construction and arrangement of the parts, all as hereinafter more particularly described, and pointed out in the claims.

In describing this invention reference is had to the accompanying drawings, forming 35 a part thereof, in which like letters indicate corresponding parts in all the views.

Figure 1 represents a perspective of my improved harrow, illustrating the general arrangement and construction of the parts. 40 Fig. 2 represents an edge view of the harrow, taken in a line at right angles to one of the front harrow-bars. Fig. 3 represents a sectional view, illustrating a harrow-tooth as secured to its supporting-bar, and illustrating 45 the leveling-bar in position; and Fig. 4 represents a perspective of an auxiliary tooth and the clip for securing the same to the upper curve of the spring-tooth.

The harrow-frame A is composed of draft-

bars *a*, arranged at an angle to the line of 50 draft, and cross-bars *b*, intersecting the draft-bars *a* and suitably secured thereto. These bars *a* and *b* are composed of suitable material, and, as illustrated, one of said bars, as *b*, is formed with a groove or recess *a'*, into 55 which the other bar is fitted for the purpose of locking the two together by the shoulders of said groove and necessitating the use of but one securing-bolt *c*.

The teeth D are attached to the harrow-bars at *d*, and are provided with a bend or loop *d'*, formed by bending the metal of the tooth rearwardly and downwardly and then forwardly. The tooth is then bent forwardly and upwardly to a point a suitable distance 65 above the plane of the harrow-frame, and the free extremity thereof is then bent backwardly and downwardly, forming a yielding digging-point *d*.

By reference to the drawings, particularly 70 Figs. 1 and 2, it will be noticed that the forward upward bend *d'* of the tooth is substantially in front of the intersecting point of the bars *a* and *b*, thus preventing material from catching in the angle formed by said bars and 75 clogging the harrow, since the said bend forces the material beneath the harrow by the runner-shaped lower bend *d'*, whence it passes rearwardly from the harrow without the slightest liability of clogging. This is a feature of great advantage, since frequently the ground to be harrowed contains quack and other materials which prevent the operation 80 of harrows as ordinarily constructed; but experience has demonstrated that with my improved construction ground of this character can be harrowed or cultivated with as much 85 ease and in as thorough a manner as ordinary clean ground.

Secured at the upper bend of the harrow-tooth by a clip D' is a smoothing or auxiliary tooth D², which is described and claimed in a preceding application and forms no part of my present invention, although particularly applicable upon a frame of this character. 90

The attaching end *d* of the harrow-tooth may be secured to either side of either of the harrow-bars, but as illustrated and preferably 95

constructed the said end is disposed in substantially a horizontal plane and fitted or recessed in a groove or recess provided in the lower side of the harrow-bars, and is secured 5 in operative position by the bolt *c*, which secures together the harrow-bars.

In order to further prevent the harrow-frame from clogging and facilitate its successful and efficient operation, I provide a leveling-bar *E*, supported in a plane below that of the harrow-frame, and preferably beneath the forward harrow-bars.

In my preceding application, Serial No. 328,971, I have illustrated a harrow-frame of 15 a different construction provided with a like leveling-bar, but in the aforesaid application the leveling-bar is supported directly upon the lower bend of the teeth secured to the harrow-frame bar superimposed above said 20 leveling-bar, while in this construction I prefer to use a brace or connection *e*, interposed between and connected to the front harrow-bar and the leveling-bar *E*. It will be understood that with this construction all strain 25 is removed from the teeth and they are free to yield to obstructions, whereas in the former construction they were somewhat hampered by the leveling-bar.

It will be readily understood that in operation the leveling-bar smooths off the ground to be harrowed and affords a bearing for the harrow, which prevents it from diving and irregular movement. By the use of this leveling-bar I am enabled to use a higher frame 35 than ordinary, and thus, in connection with

the runner-shaped bend *d* and *d'*, absolutely prevent the clogging of the harrow.

The operation of my invention will be readily understood from the foregoing, and it is evident that this construction of harrow possesses features of great advantage. I do not, however, limit myself to the exact form and construction of the parts of my harrow, since it will be understood that they may be varied from that described without departing from 45 the spirit of my invention.

Having thus fully described my invention, what I claim as new, and desire to secure by Letters Patent, is—

The herein-described harrow, the same being composed of intersecting frame-bars secured together, a leveling-bar rigidly connected to said frame-bars with a space between the two, and spring harrow-teeth secured to said frame-bars and having a downwardly-extending bend or loop extending beneath the frame-bars for forming a runner, and a yielding digging-point below the plane of said leveling-bar, substantially as described.

In testimony whereof I have hereunto signed my name, in the presence of two attesting witnesses, at Deerfield, in the county of Oneida, in the State of New York, this 21st day of January, 1890.

DE WANE B. SMITH.
